(No Model.)

C. A. WHITE.
CORN SHELLER.

No. 595,359.

Patented Dec. 14, 1897.

THE NORRIS PETERS CO., PHOTO-LITHO., WASHINGTON, D. C.

UNITED STATES PATENT OFFICE.

CHARLES A. WHITE, OF TOWANDA, ILLINOIS.

CORN-SHELLER.

SPECIFICATION forming part of Letters Patent No. 595,359, dated December 14, 1897.

Application filed February 23, 1897. Serial No. 624,629. (No model.)

To all whom it may concern:

Be it known that I, CHARLES A. WHITE, residing at Towanda, in the county of McLean and State of Illinois, have invented a new and 5 useful Corn-Shell, of which the following is a specification.

This invention relates to corn-shelling machines, and more particularly to an improved corn-sheller adapted to be used in connection 10 therewith.

One of the objects of my invention is to provide a cylinder so constructed as to be easily revolved and so constructed that provision will be made for the reception or dis- 15 charge of the grain upon the cob.

A further object of the invention is to provide a corn-sheller so constructed that the cobs can be broken up and the parts constituting the construction always kept in a clean 20 condition.

With these and other objects in view my invention consists in certain novel features of construction and combinations of parts more fully described hereinafter and partic- 25 ularly pointed out in the claims.

Referring to the accompanying drawings, illustrating my invention, Figure 1 is a view in side elevation of a corn-sheller constructed in accordance with my invention, part of the 30 cage-bars being omitted to more clearly illustrate the interior. Fig. 2 is a view in side elevation of the interior mechanism removed from the cage, the upper hub being shown in section. Fig. 3 is a transverse sectional view on the line 3 3 of Fig. 2. Fig. 4 is a transverse sectional view on the line 4 4 of Fig. 1. Fig. 5 is a plan view of the lower cage-bar ring detached. Fig. 6 is a detail perspective view showing all the parts of the interior 40 mechanism detached.

Like letters of reference mark the same parts wherever they occur in the various figures of the drawings.

In carrying out my invention I employ an 45 ordinary shelling-machine (comprising a cage or shell with hopper-mouth) and within the same I locate my improved sheller, the same comprising the ordinary shaft A, having the hubs or extensions B, in which the shaft is 50 secured, the shaft of course extending therethrough, so as to permit of the usual drawing

mechanism. The hubs or extensions B are provided on their outer peripheries with the slots C to secure the ends of the curved bars D E, a casing or cap F surrounding said hub, 55 so as to hold the end of the bars or blades D in place. These blades are curved, as shown, with the depressed central portion and are so arranged that while the upper curved end D' of one blade will be secured to the hub the 60 same end of the opposite blade will be curved upwardly, while its lower portion will correspond to that of the curved end D', so that both of them will be secured in about the same manner to the hub. The ends of the 65 blades are twisted, as shown, so as to form the flat portion adapted to enter the slot in the outer periphery of the hubs or curved portions.

The shaft A is provided with the suitable 70 pulleys for driving it, as at H, Fig. 1, and the cage is composed of upright bars i, set in rings J, K, and L and a semiring M at the upper end, half this ring being omitted to provide for the entry of the corn to be shelled, a feed- 75 hopper N being provided, as usual.

It is evident that the cobs carrying the grain can enter at one end and be discharged at the other, the blades not only tending to remove the grain from the cob, but also to 80 break the cobs.

The invention is very simple in construction and composed of a minimum number of parts, and by reason of its peculiar construction I am enabled to produce a device for the 85 purpose intended far more simple in construction and inexpensive than any heretofore employed.

It is evident that various slight changes might be made in the forms, constructions, 90 and arrangements of the parts described without departing from the spirit and scope of my invention. Hence I do not wish to limit myself to the precise construction herein set forth, but consider myself entitled to all such 95 changes as might fall within the spirit and scope of my invention.

Having thus fully described my invention, what I claim as new, and desire to secure by Letters Patent of the United States, is—

1. A corn-sheller comprising the collars or hubs carried thereby, the slots in the periph-

ery of the same, and the blades or bars curved as described and adapted to have their ends secured therein as set forth.

2. A corn-sheller consisting of the shaft 5 carrying the hubs or collars on their rear portions, the slots formed therein as described, the curved blades or bars having the reduced ends to enter the said slots and a band surrounding said hub or collar, for the purpose 10 set forth.

3. A corn-sheller consisting of the shaft carrying the collars or hubs at its ends, the slots formed on the outer periphery as described, the curved blades or bars provided 15 with the twisted and reduced ends adapted to enter the slots of the hub or collar, and a band

surrounding said collar and the ends of the curved bar resting in the slots for the purpose set forth.

4. A corn-sheller consisting of the shaft 20 carrying the collars or hubs formed integral near the end portions thereof and provided with the slots, the curved bars or blades having the twisted and reduced ends, the flattened or reduced ends being adapted to enter 25 said slots, and a band surrounding the hub or collar to hold the blades in the desired position, substantially as set forth.

CHARLES A. WHITE.
